UNITED STATES PATENT OFFICE.

EDWARD LUSCOMBE EVENS, OF MALVERN, SOUTH AUSTRALIA, AUSTRALIA.

FIRE-ESCAPE APPLIANCE.

SPECIFICATION forming part of Letters Patent No. 735,484, dated August 4, 1903.

Application filed October 17, 1902. Serial No. 127,634. (No model.)

To all whom it may concern:

Be it known that I, EDWARD LUSCOMBE EVENS, solicitor, a subject of His Majesty the King of Great Britain and Ireland, residing 5 at Clifton street, Malvern, in the State of South Australia, Commonwealth of Australia, have invented certain new and useful Improvements in and Connected with Fire-Escape Appliances; and I do hereby declare that 10 the following is a full, clear, and exact description of the same.

My invention relates to certain improvements in and connected with fire-escape apparatus and the like, and refers more specifically, first, to a cage of novel construction for the accommodation of firemen and others, and, secondly, to apparatus used in combination therewith and arranged, as hereinabove specified, for enabling the cage to be raised, lowered, and controlled, so that it may be made accessible for rescue and other purposes at almost any part of the exterior of a building.

My invention may also be applied to analogous purposes, such as the landing of passengers from ships and for mining and quarrying requirements.

In order to achieve the object of my invention, I provide a cage which is characterized 30 by a rigid vertical center pole, to which suitable hooks or shackles are attached at both top and bottom. At the bottom of this pole I construct a foot-rest or platform, and at a height of three feet, or thereabout, above the platform I place a hand-rail and an intermediate foot-rest. The bottom portion of the cage may be inclosed with wire-netting. Near the top of the pole I also arrange a horizontal cross-bar, which is likewise for use as a foot-rest or as a handhold. Various fittings in the form of rings or loops, of metal or leather, are added for the accommodation and retention of fire-hoses and other appliances. At 40 or near the top of the building I construct a light overhanging tramway or rail, the same being mounted upon or supported by suitable overhanging brackets. On the tramway I place a truck or traveling tackle, which is connected by means of wire rope to the top 50 of the center pole of the cage in order to assist in raising or lowering the latter. In addition to such wire rope auxiliary ropes are

added for the purpose of traversing the truck backward or forward along the tramway, such rope being placed over pulley-wheels arranged at the ends of the tramway and connected with alarm apparatus. Holding-rings, cleats, or other convenient devices are securely fastened in suitable positions upon the building or adjacent thereto, and a pipe or cover is also provided for the accommodation of the ropes and as a means of protection against the weather.

In order that my invention may be the better understood, I will now proceed to describe 65 the same by aid of the accompanying illustrative drawings, wherein—

Figure 1 is a front elevation of a building, showing the general arrangement of my invention as applied thereto. Fig. 2 is a detail 70 of the cage, on a larger scale; Figs. 3 and 4, side and end detail of portion of truck, showing alarm apparatus connected therewith.

In all figures similar letters of reference are used to denote similar or corresponding parts 75 wherever they occur.

In this respect and referring first to Fig. 2, *a* is the vertical center pole of the cage and is provided with hooks or shackles *b* and *c* at both top and bottom.

d is the foot-rest or platform, which is firmly attached to the base of the center pole.

e is a hand-rail or guard of any convenient shape, but preferably rectangular and oblong, as illustrated.

f is a cross-bar which passes through the center pole below the level of the hand-rail and may be used either as a foot-rest or a seat. Without confining myself to any specific size I prefer to make the center pole about six to 90 eight feet in height, and at a distance of about one foot from its top I place an upper cross bar or bars *g*, which serve as handholds, seats, or ladder-rungs, according to the position assumed by the firemen or other occupants of 95 the appliance.

h are loops, preferably of metal, for the retention of fire-hoses, guide-ropes, or such other appliances as it may be found necessary to add to the cage. In the smaller illustration of the cage I have shown a convenient-shaped fender or screen *i*, placed around the appliance, the same being intended to serve the purpose of a guard and also to as-

sist in deflecting the cage should it come into contact with parapets or other projecting portions of the building in its descent.

5 *j* is the face of the building. In a suitable position, but preferably above the uppermost parapet, I arrange a series of strong brackets *k*. These may be of any convenient design and are used for the purpose of supporting the tramway or rails *l*, the arrangement being such that the traveling truck *m*, which is mounted thereon, is free to traverse the whole length of the building without impediment. This tramway may be extended to the sides and back of the building, if so desired. The 10 truck to be used may vary in design, but supports the pulley sheave or block *n*.

15 *o* is a chain or wire rope which when in operation is fastened to the vertical center pole of the cage, but when not in use is intended to have its free ends joined together, so as to form an endless rope. In order that this rope may be readily accessible in cases of emergency and at the same time be protected from inclement weather, I provide an open down-pipe or cover *p* for its reception.

20 *q q* are pulley-wheels mounted in bearings upon the upturned portion of the truck-rails *l*, conveniently placed at the ends or sides of the building, and over which the traverse-ropes *r* are passed, the said traverse-ropes being connected with the traveling truck *m* at one end. The opposite end, which is held taut by counterbalance-weights, is fastened to or accommodated in any convenient reception-tacle.

25 *s s* are rings or cleats which are securely fastened to the building for the purpose of affording a purchase or grip to the chain or rope *o* when the latter is to be operated.

30 At each end of the building and to an extension of the shafting which carries the pulley-wheels *q q*, Figs. 3 and 4, I attach a screw end *t*, which is preferably constructed on the Archimedean principle.

35 *u* is a nut which is designed to travel freely from the screw end and is weighted on one side, as illustrated, so that when the shaft is rotated the weighted portion has a tendency to prevent the nut from revolving in unison with the shaft and allows it to move horizontally in proportion to the pitch of the screw. The screw ends at opposite ends of the building are formed, respectively, with right and left handed threads, so that whichever way 40 the traverse-ropes are hauled one of the weights will be detached.

45 *v* is a guide or receptacle placed beneath the free end of the screw *t* and in which the electric terminals *w w* are arranged, such terminals being connected with alarm-bells in various parts of the building (not shown in the drawings) and with alarm-signal apparatus at the fire-station.

50 The method of using the apparatus is as follows: In event of an outbreak of fire the chain or rope *o* is slipped from beneath its cover *p*, and one end of it is attached to the upper

portion of the cage. The other end may either be attached to the bottom portion of the cage to serve in some degree as a guide-rope, as well as for hauling purposes, or, additionally, an independent guide-rope may be attached to the bottom of the cage. By means of the traverse-ropes *r* the line of ascent may be adjusted to the most convenient position for coping with the fire, and as the traverse-ropes pass over the pulleys *q q* the extensions *t* are caused to rotate, the result being that one of the nuts *u* traverses along to the end of the extension, so that it falls off 55 into the guide or receptacle *v* and immediately makes contact with the electric terminals *w*, thereby giving the alarm to the inmates of the building and simultaneously effecting a communication with the fire-station. The mechanism may be put into operation before any other steps are taken to use the escape.

60 It will readily be understood from reference to the drawings that the combined appliance affords facilities for escape from almost every part of the building, while the general construction of the cage renders it suitable for ladder or scaling purposes for obtaining access to and from the roof and other parts. 55 The rings or cleats at the base of the structure enable a grip to be obtained for holding the hauling-rope and may be provided with a simple or compound pulley-block and tackle.

65 In practice firemen sometimes arrange a pair of portable ladders at each side of a burning building and connect them with a horizontal rope or cable, which is substantially at the level of the windows of a floor, facilitating the escape of the occupants of that floor. My truck *m* could be arranged to run upon such a rope instead of upon the permanent track *l* intended for it.

70 I find by experiment that the use of a rigid center pole arranged in the manner indicated in connection with the cage minimizes the oscillation and affords considerable comfort to the occupants.

75 Having now particularly described and ascertained the nature of my said invention and in what manner the same is to be performed, I declare that what I claim is—

80 1. In a fire-escape, in combination, a truck adapted to be moved transversely of a building, lines leading therefrom, pulleys over which said lines pass, said pulleys having threaded extensions, nuts carried thereby, and means whereby said nuts may close an electric circuit.

85 2. In a fire-escape, in combination, a cage which may have a transverse movement, pulleys adapted to be moved when said cage moves, said pulleys having threaded axial extensions, nuts carried thereby which become disengaged by a continued movement of said pulleys, and means whereby said nuts may close an electric circuit when disengaged.

90 3. In a fire-escape, in combination, a mov-

able truck adapted to be moved transversely of a building, a cage therebelow, tackle apparatus supporting said cage, lines leading from said truck, pulleys arranged at the side of said building and over which said lines pass, and means whereby the rotation of said pulleys may close an electric circuit.

4. In a fire-escape, in combination, a track adapted to be disposed transversely of a building, a truck mounted thereupon, lines connected to said truck, pulleys arranged at the side of said building, threaded members adapted to be moved by the rotation of the said pulleys, said lines passing over said pulleys, and means whereby said threaded members may close an electric circuit.

5. In a fire-escape, in combination, a truck

adapted to move transversely of a building, a cage therebelow, tackle apparatus suspending the same from said truck, lines leading from said truck, pulleys arranged at the side of said building, and over which said lines pass, counterweights carried by said lines, means whereby the movement of said truck may close an electric circuit, and a vertical pipe adapted to normally contain said tackle apparatus.

In witness whereof I have hereunto set my hand in presence of two witnesses.

EDWARD LUSCOMBE EVENS.
